United States Patent Office.

WILLIAM TRIPP, OF EPSOM, NEW HAMPSHIRE.

Letters Patent No. 79,614, dated July 7, 1868.

IMPROVEMENT IN WOOD-SAW HORSES.

The Schedule referred to in these Letters Patent and making part of the same.

TO ALL PERSONS TO WHOM THESE PRESENTS MAY COME:

Be it known that I, WILLIAM TRIPP, of Epsom, in the county of Merrimack, and State of New Hampshire, have invented a new and useful Improvement in Saw-Horse; and I do hereby declare the same to be fully described in the following specification, and represented in the accompanying drawings, of which—

Figure 1 is a top view,

Figure 2 a front elevation, and

Figure 3 a transverse section of a saw-horse, provided with my invention, the plane of section being taken through the devices employed for holding the log in the crotches of the frame.

The invention or improvements may be said to consist in—

An adjustable clamp-arm, secured to its bar by means of notches fitting on a pin, and by a wedge, as hereinbefore described.

Also, in the combination of a treadle, a rocker-shaft, a bar, and an arm, the whole being constructed substantially in manner and so as to operate as hereinafter explained.

The frame of the horse is represented as composed of three sets of crossed bars, *a a b b c c*, arranged and connected by three bars, *d e f*, disposed, as shown in the drawings. The auxiliary set of crossed bars, arranged with respect to the other two, and the mechanism for holding the log down, renders the horse much more useful for holding very long sticks, as the auxiliary set of crossed bars, by supporting the stick, prevents the weight of it (at the end so supported) from pressing the log-holder upward against the downward pressure of the leg of the sawyer on the treadle of the holder.

Between the two sets of crossed bars, *b* and *c*, the log-holder is arranged. It consists of a treadle or pedal, *g*, a bar, *h*, and an adjustable arm, *i*. The pedal turns on the lower bar *e*, and projects in opposite directions therefrom, in order that the heel of a person's foot, when pressed on the shorter arm of the treadle, may depress it and force up the longer arm, the latter being depressed by the foot being forced down upon it.

The bar *h* is hinged or jointed to the treadle, and extends up through and so as to slide freely in a rocker-shaft, *k*, arranged between and pivoted to the two sets of cross-bars *b c*. The arm *i* slides freely on the bar *h*, which passes through the arm, and has a series of notches, *l l l*, made in it, as represented, they being to receive a pin, *m*, which goes through the mortise of the arm. A wedge, *n*, driven down into the mortise, is used to drive the pin into either of the notches, so as to set the arm at any desirable elevation, according to the size of the sticks or logs to be sawed. The rocker-shaft, by turning with the bar *h* during its motions, steadies it much better than a single eye or staple would.

I am aware of the patent, No. 31,605, dated March 5, 1861, and granted to George Ives. I make no claim to the invention covered by such patent.

I am also aware of the saw-horse described in patent No. 13,755, such saw-horse having three sets of crossed bars, but it has not my arrangement of the log-holder with respect thereto, my log-holder being arranged between two of them. My said arrangement saves the necessity of putting the log-holder within the middle set of bars, and enables it to be worked by a treadle, and the latter to be arranged between the two sets of bars. Furthermore, it affords advantages in holding the wood for being sawed.

I therefore make no claim to anything described in the said patent, No. 13,755; but

What I do claim as my invention is as follows:

I claim the adjustable clamp-arm *i*, as applied to the bar *h* by means of the notches *l*, fitting on the pin *m*, and as secured by the wedge *n*, substantially in the manner described.

Also the combination of the treadle *g*, rock-shaft *k*, bar *h*, and arm *i*, constructed to operate as and for the purposes set forth.

WILLIAM TRIPP.
